YARN TWISTING MACHINE

Norman E. Klein, Pendleton, S. C., assignor to Deering Milliken Research Corporation, near Pendleton, S. C., a corporation of Delaware

Application September 1, 1951, Serial No. 244,812

14 Claims. (Cl. 57—58.86)

This invention relates to yarn twisting devices for use in the textile industry and, in particular, to twisting machines of the type which impart two twists in the yarn for each revolution of the twister spindle.

Heretofore, many attempts have been made to employ the two-for-one twisting principle as a means of increasing the rate of yarn production. In some instances, the gain in twisting rate was substantially offset by the required reduction in spindle speed in order to maintain the resulting balloon diameter within reasonable confines, as dictated by the gauge of existing standard commercial upright twisting frames. I have discovered, as set forth in my copending application, Serial Number 133,047, filed December 15, 1949, now Patent No. 2,731,786, that the two-for-one principle can be employed to provide a twisting spindle that is compact in size and which will operate on standard commercial upright frames at substantially higher speeds than heretofore practiced with conventional one-for-one spindles, thereby increasing the rate of yarn production from two to four times that of the conventional spindles. While the twister described in my aforesaid application is a marked improvement over prior art devices, I have discovered that simplification of structure together with other improvements have made it possible to materially extend the usefulness of the device to a wider variety and weights of yarn.

It is, therefore, an object of my invention to provide a yarn twisting spindle of the two-for-one type that is operative on standard commercial upright twisting frames and capable of imparting a high twist at higher spindle speeds to a wider variety and weights of yarns than has heretofore been achieved.

A further object of my invention is to provide such improvements in the over-all yarn tension control in twisters of the aforesaid type, that a more uniform high twist can be imparted to a wider variety and weights of yarns than has been produced on devices of the prior art.

Briefly, the device of my invention whereby the above objects are achieved consists of an arrangement for supporting a yarn supply package in concentric relationship with a rotatable spindle that carries a conventional whorl beneath the supply package, but is provided with an improved flyer and yarn storage device. Yarn to be twisted is drawn upwardly off the package, fed downwardly through a primary tension control array supported above the package, then radially out through the spindle in contact with the yarn storage device and flyer and finally upwardly to a suitable windup reel or bobbin.

In the past, considerable difficulty has been experienced in twisting zero twist and low pre-twist yarn of the synthetic continuous filament types due to the formation of snarls in the yarn as it is withdrawn from the supply package. I have overcome this difficulty by the provision of a simple yarn pretensioning device positioned between the yarn package and the primary yarn tensioning array. Just enough tension is provided to prevent the free unwinding of yarn. The pretensioning device also prevents relative creep of individual fibers of the

2

yarn which causes snarls to form, particularly in zero twist yarn.

A further feature of my invention resides in improvements in the primary tension array which is so constructed to automatically respond to variations in input tension as may arise from variations in yarn diameter, non-uniform sizing treatment or drag in withdrawal from the supply package, so as to maintain the output tension more nearly constant. The improved primary tension array also makes provision for easy and rapid adjustment of tension and, above all, is so constructed to accommodate substantially all continuous filament synthetic yarns known in the textile industry at the present time. The improved tension array is also effective to properly regulate tension of yarns of a wide range of denier or weight.

Another feature of my invention which has materially aided in making the two-for-one twister a universal machine with respect to its yarn handling ability resides in an improved yarn storage arrangement associated with the flyer. I have discovered that the control of the balloon diameter in upright twisters of the type here under consideration is dependent upon the selection of the proper ratio of flyer to yarn storage device diameter and this ratio, in general, must increase with an increase in yarn denier or weight. In order to provide a proper regulation of tension to maintain a constant balloon diameter for different weight yarns as well as yarns differing in basic constituency, the wrap around surface of the yarn storage device is given a spiral configuration in part only. Such surface provides, with the required limits, an increasing moment arm for feeding energy into the balloon with increases in wrap around thereby causing the yarn storage device to properly stabilize the yarn balloon for different yarns.

My invention also contemplates the provision of a simplified arrangement for magnetically stabilizing the yarn supply support platform. This arrangement also automatically functions to apply a braking force to stop rotation of the platform in the event of inadvertent rotation thereof.

Other objects and advantages of the invention, as well as details of construction of the preferred embodiment thereof, will become apparent from the following description when read in connection with the accompanying drawings in which:

Figure 1 is a vertical sectional view partly in elevation of a two-for-one twister embodying the invention;

Figure 2 is a plan view of the pretensioning device forming part of the twister of the instant invention;

Figure 3 is an enlarged vertical sectional view of the primary tensioning array of the twister shown in Figure 1;

Figure 4 is an elevation view partially in section of the tension array viewed at right angles from that shown in Figure 3;

Figure 5 is a schematic view of the primary tensioning device of Figures 3 and 4, illustrating the principle of operation;

Figure 6 is an enlarged cross-sectional view taken along the line VI—VI of Figure 1, showing further details of the twister flyer and yarn storage device;

Figure 7 is a fragmentary top plane view of the twister, principally showing the combined magnetic stabilizer and brake; and

Figure 8 is a sectional view of the magnetic stabilizer and brake assembly, as viewed along line VIII—VIII of Figure 7.

In Figure 1 of the drawings, the reference numeral 10 designates a portion of a conventional twister frame having an upstanding bracket 12 to which is hinged a swing gate 14 of conventional design. The swing gate 14 supports a bolster 16 resiliently clamped to an extension 21

of the swing gate by a nut 18 bearing against a spring 20 disposed about the bolster. Further resilience is maintained by the use of a felt washer 22 and a felt sleeve 24 disposed as shown.

The bolster 16 carries an upstanding rod 26 about which a whorl 28 is journaled and adapted for rotation on antifriction bearings, such as ball bearings 30. The upper end of the whorl 28 has an upstanding tubular extension 32 which terminates in a tapered portion to receive a ball bearing 34. The ball bearing 34 is arranged to support a cup-shaped yarn supply package support 36. The yarn supply package support 36 has a concentric upstanding tubular central portion 38 terminating in an annular ledge 40. The package support 36 including the upstanding central portion 38 may be constructed of metal either cast or machined or both to secure the desired configuration. It may also be molded of suitable plastic material.

A sleeve 42 is connected threadwise to the upper end of the tubular central portion 38 and is adapted to receive and support a tubular pedestal 44, which makes threaded engagement intermediate its ends with a threaded portion at the upper end of the sleeve 42. It will thus be seen that as the pedestal 44 is screwed downwardly the ball bearing 34 will be firmly clamped between the annular ledge 40 and the lower end of the pedestal. Rubber rings 46 are disposed on either side of the ball bearing 34 so as to provide absorption of vibrations as may be caused by high speed rotation of the whorl 28 and the parts carried thereby.

The yarn supply 48 is held within the cup-shaped package support 36 and preferably is wound on a bobbin 49 having an upper flange 51 and a circular handle 53 of the form shown in my copending application, Serial Number 249,547 filed October 3, 1951, now Patent No. 2,756,006.

The bobbin 49 with yarn supply 48 and the pedestal 44 are enclosed by a plastic, transparent cover member 50 which is provided with a tapered circumferential flange at its lower end to frictionally engage a complementary flange on the upper end of the package support 36.

Disposed within the cover member 50 is a yarn pre-tensioning device consisting of a ring 52 provided with a plurality of inwardly extending bristles 54. The ring 52 is preferably positioned at a level intermediate the flange 51 of the bobbin 49 and the rim of the circular handle 53. The individual bristles may be formed of nylon or other suitable plastic material and are preferably cemented to the ring 52 and disposed at an angle of approximately 45° with reference to their respective tangent to the ring, as more clearly shown in Figure 2. The purpose and operation of the ring and bristles will be more fully described hereinafter.

The ring 52 may be secured to the inner wall of the cover member 50 in any suitable manner, such as the means 56, including a plurality of at least three detents formed integrally with the cover member. The ring 52 is placed in position by forcing it beyond the detents and, thereafter, is frictionally held in the desired position.

The tubular pedestal 44 has a conical yarn guide cap 58 provided with a centrally disposed yarn passage 60. Immediately below the cap 58 and arranged within the pedestal 44 is a primary yarn tensioning array generally designated at 62. The primary tensioning array comprises coating stationary and movable elements between which the yarn is adapted to be drawn and because of the particular arrangement of these elements, as will be presently described, the tension array may be said to be of the gate type. The stationary elements in this instance may be in the form of a plurality of rods or pins constructed of case-hardened steel or ceramic material and set transversely across the bore of the tubular pedestal 44 slightly disposed to one side of the diametrical

center. The rods 64 are preferably evenly spaced in the axial direction of the pedestal 44 and held in position by frictional engagement with suitable openings extending through the walls of the pedestal. The movable elements of the tensioning array comprise a plurality of spaced transversely extending bars 66 of generally rectangular cross section. The bars 66 may be formed of case-hardened steel or of a ceramic material. In either instance, the edges of the bars 66 facing the pins 64 are given an arcuate configuration slightly concave so as to assist in centering the yarn as it is drawn between the stationary and movable elements. The movable elements 66 are arranged in spaced relationship adjacent one end of a movable arm 68. The spacing of the bars 66 is such that they will freely interleave or interdigitate with the rods 64 but without producing physical contact therewith. Any suitable means may be employed to secure the bars 66 to the arm 68 such as by welding or clamping in the event that steel is employed or as by cement in the event that the bars 66 are constructed of a ceramic material. While the stationary and movable elements 64 and 66 have been illustrated respectively as pins and bars, it is obvious that a large variety of equivalent structures could be substituted provided such structures present a plurality of smooth hard yarn engaging surfaces about which yarn may be caused to wrap when the respective elements are brought into operative relation.

The lower end of arm 68 has a bifurcated construction, each leg of which terminates in a knife edge 70, as more clearly shown in Figures 3 and 4. A circular plug 72 makes a sliding fit with the lower end of the pedestal 44 and is provided with two rather shallow V-shaped grooves disposed in diametric alignment across the upper face of the plug, one on each side of a central opening 76 provided for the downward passage of yarn. It will thus be seen that arm 68 carrying the tensioning bars 66 may be rocked about the knife edges 70 to a limited amount so as to move the bars 66 toward and away from the stationary rods 64. Proper alignment of the bars 66 with respect to the rods 64 is obtained by adjusting the position of plug 72 within the tubular pedestal 44. When the proper alignment has been made, the plug 72 may be fixed in position by means of set screws 78 screw-threaded through the side wall of the pedestal.

The arm 68 has an aperture 80 provided therethrough intermediate its ends for the reception of the tongued end 82 of a leaf spring 84 bowed, as shown, so as to be capable of exerting a force in a direction generally longitudinally thereof when stressed. The upper end of the spring 84 has an offset portion 86 rounded at its free end to a relatively small radius and arranged to bear on the surface of an internal annular re-entrant groove provided at 88 in a knurled collar 90. The collar 90 is screw-threaded, as shown, about the pedestal 44 to provide an adjustment of the tension of the spring. An opening 92 extending longitudinally of the pedestal 44 accommodates the spring 84 in the position shown and also provides access to the movable elements of the tension array. A handle 94 extending from the upper end of the arm 68 projects outwardly and may be grasped by the operator so as to rock the arm 68 outwardly to an open position when it is desired to thread the device prior to starting a twisting operation.

The upper end of arm 68 is also provided with a curved portion extending substantially at right angles to the main portion of the arm and to which is secured a tension plate 96. Coating with the tension plate 96 is a similar plate 98 resiliently and slidably mounted for movement in a horizontal direction. This particular mounting is accomplished by the provision of two ears 100 formed integrally with the plate 98, each having an aperture therethrough for the passage of support rods 102. The support rods 102 have horizontal portions along which the plate 98 may slide and are provided with an upturned portion anchored in the cap 58. The movable plate 98

is resiliently biased lightly toward the plate 96 by means of a leaf spring 104, the lower end of which is secured to the inner wall of the pedestal 44 by a screw 106.

The plug 72 also supports a thread guide 108 which extends upwardly therefrom in alignment with the central opening 76. A complete description of the operation of the yarn tensioning device 62 will be given later in connection with the over-all operation of the twister.

The upper end of the whorl 28 has a sleeve extension 110 to which is secured a flanged flyer hub 112. Secured to the flange of the flyer hub 112, as by riveting, is a flyer 114 having a shallow, generally cup-like shape and constructed of metal, plastic or other suitable material. The lower portion of the flyer hub 112 is provided with a continuous groove portion 116 spiral-like in part which serves as a yarn storage device, the operation of which will be more fully described hereinafter.

The tubular extension 32 has an arcuate slot 118 cut therein adjacent its lower end so as to provide a passage to a thread guide tube 120 disposed within the extension. The lower end of the thread guide tube 120 has a ceramic bead insert 122 thereon to serve as a wearing surface for the yarn passing therethrough. A diamond-shaped opening 124 in the sleeve 110, disposed in alignment with the slot 118, provides means for bringing the yarn out of the spindle. The yarn emerging from the opening 124 is directed through a notch 126 provided in the yarn storage device 116. As indicated more clearly in Figure 6, the yarn storage device 116 has a surface at 128 in the form of a groove extending in either direction from the notch 126, increasing in radius in spiral-like manner through about 120° and then merging with a surface at 130 having a constant radius. The surface 130, however, is disposed at a higher level, as more clearly shown in Figure 1. The stepped surfaces 128 and 130 are slightly tapered inwardly from the bottom to the top to facilitate yarn movement upwardly from the lower to the higher step. It is, thus, seen that the yarn storage arrangement provides a stepped wrap-around surface in the form of a sheave which gradually increases in radius from a lower to a higher step. The yarn end emerging from the yarn storage device is directed upwardly in contact with the flyer 114 through a fixed guide 132 to a suitable take-up package or bobbin.

In the event of yarn breakage outside the spindle, the tail end issuing from the opening 124, unless it is restrained in some manner, will continue to feed outwardly due to the centrifugal force acting thereon occasioned by a high spindle speed. Obviously, the continued feeding of yarn through the spindle when an end is broken will cause lint to become entangled with the spindle or even interfere with the operation of adjacent spindles on the same frame. This problem of yarn feed through is solved by the provision of means for severing the yarn adjacent the spindle opening. Disposed within the sleeve 110 is a split ring 131 of spring sheet steel or the like which may be fastened to the sleeve by rivets as shown in Figure 1. The split in the ring 131 is aligned with the diamond shaped opening 124 so as not to interfere with the normal passage of yarn therethrough but coats with one or the other of the V-shaped sides of the opening to cause the yarn tail to be severed adjacent the spindle opening. The free end of the yarn within the spindle is also held between the ring 131 and the sleeve 110 so that the yarn will no longer feed through the opening 124. For a further disclosure of this particular feature reference may be had to my copending application, Serial Number 179,069, filed August 12, 1950, now Patent No. 2,625,786, wherein the feature is specifically described and claimed.

The yarn supply package support 36 is held against rotation during the operation of the twister by means of a magnetic stabilizer, more clearly shown in Figures 7 and 8. To the swing gate 14 is secured a rearwardly extending arm 134 that has an upstanding bracket 136 arranged

adjacent the yarn supply package support 36. A slotted magnet support member 138 is mounted for limited rocking movement on the end of bracket 136 by means of a pin 140, as shown.

5 A U-shaped permanent magnet 142, preferably of high permeability, is clamped to the lower end of the support member 138 by means of a clamping plate 144 and screws 146, only one of which is shown. The yarn package support 36 has a cold rolled steel insert 148 10 inserted in the vertical wall thereof in general horizontal alignment with the open ends of the magnet 142 when the magnet support member 138 is in the position as shown in Figure 8. In this position, the magnetic attraction of the magnet 142 for the steel insert 148 15 maintains the yarn supply support 36 in fixed position, thereby overcoming the tendency of the support to rotate.

The upper portion of the support member 138 has an arcuate surface 150 which is grooved to receive a strip of resilient material, such as rubber tubing, to serve as a 20 brake surface. The tubing 152 may be retained in position by means of a wire 154 threaded therethrough and passing about the transverse leg portion of member 138, as shown.

The combined mass of the magnet support member 138 25 and the magnet 142 is so arranged with respect to the axis of rotation about the pin 140 that, when the attraction between the magnet and the steel insert 148 is removed, the member 138 will rotate about pin 140 in counterclockwise direction, as viewed in Figure 8.

30 It will, thus, be seen that in the event that the magnetic attraction between the magnet 142 and the steel insert 148 is not sufficient to hold the support 36 against inadvertent rotation the magnet support 138 will rotate in a 35 counterclockwise direction bringing the brake surface 152 into contact with the side of the support 36 to arrest rotation thereof.

A chain 156 may be employed to connect the upper 40 end of the magnet support 138 with an appropriate portion 158 of the twister frame by means of suitable fastening means 160 and 162, as indicated. The length of chain 156 is so selected that it will permit sufficient angular movement of the magnet support 138 to engage and stop the yarn supply support 36 in the event of rotation thereof, but becomes taut when the swing gate 14 is 45 moved from an operative to an inoperative position. The chain 156 thereby causes the rocking magnet support 138 to be rotated in a clockwise direction to the upright position, as shown in Figure 8 making it ready automatically to again perform its magnetic stabilizing position. The 50 yarn supply support 36 may then be rotated until the steel insert 148 is again adjacent to the open end of the magnet 142. The magnetic attraction between the magnet support 138 in the upright position so that the spindle 55 may be returned to the operative position by movement of the swing gate 14 until the whorl 28 is in contact with the conventional driving belt.

In order to prevent broken ends or lint developed at 60 any one spindle position from interfering with an adjacent spindle position on the twister frame, I have provided an arcuate-shaped shield 164 which may be supported from the edge of the arm 134 and held in position by a plurality of screws 166. The shield 164 is spaced a sufficient distance from the yarn supply support 36 to 65 prevent contact with the yarn balloon.

The specific function of the several components of the device of my invention during a twisting operation will 70 now be described. In threading up the spindle, the swing gate 14 is swung into the inoperative position so that the whorl 28 is out of engagement with the conventional drive belt. The yarn guide 132 is moved up to an inoperative position and the cap or cover 50 is removed from the yarn supply support 36. The operator now has access 75 to replace an empty yarn bobbin with yarn supply 48 wound on the bobbin 49.

The yarn end from the package 48 is twisted about one end of a long semi-flexible threading tool, commonly referred to as a "snake." By grasping the handle 94 and rocking the arm 68 in a counterclockwise direction, a sufficient separation of the tension plates 96 and 98 and also the movable tension bars 66 from the fixed pins 64 may be obtained to allow passage of the snake therebetween. The snake is then passed downwardly through the opening 60 in the cap 58, through the primary tension array 62, and then successively through the guide tubes 108 and 120 and the bead 122, being deflected at this point by the arcuate slot 118 and caused to emerge through the diamond-shaped orifice 124. As the snake is pulled through, this yarn end is threaded into the proper flow path. The cover 50 is replaced, the guide 132 is lowered and the yarn is brought upwardly over the side of the support 36 and the cover 50 and, after threading through the guide 132, the spindle is started by rotating the swing gate 14 to operative position so that the whorl 28 is rotated at high speed as a result of engaging the conventional belt drive. As the twisting operation begins, the yarn end is secured to the take up bobbin in the usual manner.

The flyer 114 and its hub 112 rotating with the whorl causes the yarn to be drawn into the notch 126 and driven in a spiral path about the support 36 and the plastic cover 50, the generatrix of the yarn or balloon taking the general shape of the support and cover but without engaging the outer surfaces thereof. For each revolution of the flyer 114, two twists are imparted to the yarn.

The imparting of a high twist at high linear yarn speeds for a variety of kinds and weights of yarn brings into play the cooperative action of all yarn tensioning devices herein provided. For example, in the twisting of low initial twist continuous filament acetate yarn of 75 denier, there is a tendency for the yarn to unwind too freely from the package 48 and produce snarls as it enters the passage 60 above the primary tensioning array 62. There is also a tendency for the individual fibers of the yarn, particularly of a zero twist type of yarn, to creep with respect to each other, thereby causing snarls to form. This snarling is avoided by the use of the pretensioning bristles 54. The bristle support ring 52 is so positioned in the cover 50 that the bristles extend inwardly and circumferentially in the general direction of rotation of the yarn as it is drawn off the supply package. As the yarn is drawn off, the bristles 54 cause it to be deflected slightly so that it makes contact with the upper bobbin flange 51 and circular handle 53 thereby increasing the drag. This arrangement provides a measure of tension regulation in that the higher the package pull-off tension, the higher the bristles will be lifted. As the bristles are lifted the pinch and wrap around actions decrease, to lessen the tension contributed by the bristle array. The approach angle of yarn, with respect to the bristles, is a relatively small acute angle so that very little tension is imparted, being only sufficient to prevent the free unwinding of yarn and the relative creep of the individual fibers. In practice, I have found that nylon bristles having a diameter in the neighborhood of .005 inch, positioned at approximately a 45° angle with respect to the corresponding tangent to the ring, provides the necessary control for yarn deniers in the range of 50 to 150.

The primary tension array 62 is largely responsible for maintaining a constant tension through the device, in spite of variations in input tension. For example, if the input tension is low, the spring 84, acting on the movable arm 68, causes the movable bars 66 to push bites of yarn between the stationary pins 64, thereby increasing the amount of yarn wrap around about the tensioning elements to equalize the output tension. As the input tension increases, the pull on the yarn passing through the tensioning array 62 increases, tending to straighten

the yarn path by moving the arm 68 against the force of spring 84 in a counterclockwise direction as viewed in Figure 3 and, consequently, decreasing the total amount of yarn wrap around to lessen the tension. In order to provide for the proper regulation of the primary tension control, I have discovered that the applied force of the spring 84 acting to rotate the arm 68 must decrease as the tensioning elements 66 and 64 are forced in the direction of separation. The arrangement most successful to accomplish the desired result embodies the toggle principle, as more clearly illustrated in Figure 5. In the illustration of Figure 5 corresponding parts, as shown in Figures 1, 3 and 4, are given prime numeral identification.

The force exerted by spring 84 may be considered as being substantially constant for all operative positions of the movable tension arm 68'. In the full line position of the arm 68' the moment of force, tending to cause rotation of the arm, is represented as F_r . At this particular position it will be noted that r is relatively small. However, in the broken line position of the arm 68' or a position of greater tension requirements, the moment of force tending to rotate the arm is F_r' . In the latter case, r' is materially larger than r . As the arm 68' is swung clockwise from the solid line position, r approaches zero as the toggle approaches its dead center position. Thus, it can be seen that, as a requirement for less corrective tension ensues, the toggle arrangement of the spring 84 and arm 68 provide the correct conditions.

The efficiency of the primary tension array is materially enhanced by the reduction of frictional loss at all pivot points. Knife-edge bearing surfaces are provided at 70 where the arm 68 pivots in the V-shaped grooves 74 and 35 the lower end of spring 84 presses against a knife-edge defining the lower edge of the aperture 80. The upper end 86 of the spring 84 makes substantially a point contact with the annular channel 88. Adjustment of the tension of the primary tension array is also greatly simplified in that it is accomplished by rotating the knurled collar 90 in the required direction to increase or decrease the tension of the spring 84.

The primary tension array 62 is provided with an auxiliary tension device in the form of the plates 96 and 98. Inasmuch as these plates precede the pins 64 and bars 66 in point of yarn travel, the plates may be properly termed pre-tension means. Their principal function, however, is to always maintain a certain minimum tension in the twister spindle, even though the tension by wrap around at the pins 64 is substantially reduced. This is accomplished by the follow-up movement given to the plate 98 slidingly suspended from the horizontal rods 102. As plate 96 moves to the left, even to a point where little or no wrap around tension is created at the pins 64 and bars 66, the spring 104 will maintain the plates 96 and 98 in tension with respect to the yarn. It will also be observed that the tension between the plates 96 and 98 decreases as the arm 68 is rotated in a counterclockwise direction as viewed in Figure 3. The decrease, however, is at a much slower rate in that the toggle action of the arm 68 and spring 84 is not directly involved.

Further yarn tensioning and control is desirable and is provided in the form of the yarn storage device 116 formed on the lower portion of the flyer hub 112. The 65 yarn storage device has as its principal function the cooperation with the primary tension array in the control of the size and shape of the yarn balloon. In operation, the yarn end emerging from the orifice 124 does not move directly radially outwardly to the periphery of the flyer 70 114 but makes a 90° bend at the notch 126 into the yarn storage device 116 and wraps itself around the yarn storage surface over a predetermined angular distance. For a particular whorl-flyer geometry this angular wrap is dependent upon the yarn material, density, spindle speed, 75 primary tension control setting and degree of twist being

imparted. The twist shows its effect through density change of the yarn which in turn effects the air drag to centrifugal force ratios establishing the particular balloon shape. The air friction or drag in this instance causes the lagging behind or wrap around effect of the yarn. The angular distance or degree of wrap around determines the relative amount of tension being provided by the yarn storage device.

That the yarn storage device assists in maintaining the proper balloon geometry will be evident from a consideration of the following operational conditions. Assuming that for a certain setting of primary tension control the input tension or drag on the yarn suddenly increases and is not completely compensated for by the primary tension control, the take-up speed being constant, there will result an increase in the over-all tension, thus causing the balloon to contract. The contracting balloon offers less air friction and causes the yarn in the balloon to speed up thereby decreasing the amount of wrap around on the yarn storage surface. Decreasing the amount of wrap around also decreases the tension, thus allowing the balloon to regain its normal size and configuration.

If the input tension should decrease without being properly regulated by the primary tension control, the yarn balloon will tend to increase in size thereby causing more air drag and a resultant increase in wrap around about the yarn storage device. The increase in wrap around is accompanied by a corresponding increase in tension, which again tends to bring the balloon dimensions down to the required size. Thus, the yarn storage device acts as a regulator, feeding the required amount of yarn into the balloon to maintain its geometry substantially constant.

In order to enable the yarn storage device to properly regulate the balloon dimensions for a wide variety of kinds and weights of yarns, approximately the first 120° of wrap around surface of the yarn storage device is disposed in the form of a spiral so that operation may be selected in the range that best fits the control requirements of the particular yarn. This need is evident from the fact that as yarn denier is increased the centrifugal force value increases more rapidly than the air drag factor. A smaller wrap around step, providing less lever arm coupling and drive, coordinates with the relatively smaller power requirement to overcome the relatively smaller air drag.

The over-all effect of the several tensioning control means embodied in my invention has made it possible to regulate the yarn balloon to such a degree that no external devices, such as wire rings or circular bands, are needed to limit the balloon diameter. The use of such confining rings or bands is a direct limitation in that certain yarns, such as thermoplastic types, will not withstand the abrading action of contact with the confining means.

The twister embodying the aforescribed features of my invention is particularly suited for handling yarn composed of synthetic fibers, such as rayon, polyamides, polyesters and polyacrylic yarns. While yarns such as silk and spun glass fiber have not been twisted on the spindle disclosed herein, it is believed that such operation would be entirely satisfactory.

It has been established that synthetic yarns of weight from 15-denier to 300 denier can be successfully handled. The number of turns per inch does not appear to be critical, the upper limit being dictated by the strength of the yarn. As a further illustration of typical performance, a particular spindle having a 1 1/3 pounds yarn capacity and set on 51 1/16 inches gage positions will handle yarns of weight from 50 denier to 150 denier at a spindle speed of about 15,500 R. P. M. Beyond this three-to-one denier range, the speed of the spindle must be varied to some degree inversely in respect to yarn size to maintain optimum balloon shape.

While I have shown and described a specific embodiment of my invention, it is to be understood that the same is for the purpose of illustration and that changes and modifications may be made by those skilled in the art

without departing from the spirit and scope of the appended claims.

The following is claimed:

- 5 1. In a two-for-one twister in which yarn travels from a yarn package to a yarn guide at the top of a normally non-rotatable tubular pedestal, then passes through the bore of said pedestal, in which region a first twist is imparted to the yarn, down to a rotating flyer, thence out through a radial passage in said flyer, up around the flyer and bobbin in substantially balloon-like manner, through a second yarn guide, a second twist being imparted to the yarn between said flyer and said second yarn guide, and finally to yarn take-up means, the improvement which comprises flexible pretensioning means located between the top of said package and the first-mentioned yarn guide to prevent kinking of the yarn in that region, primary tensioning means disposed within the pedestal for inducing tension regulation in the yarn at that region, and secondary tensioning means associated with said flyer for assisting in controlling the extent of ballooning of the yarn as it passes from the flyer to said second yarn guide.
- 10 2. In a two-for-one twister for yarn, having a support member, a flyer rotatably mounted on said support member, a yarn package support cup supported by said flyer and rotatable relative thereto, a yarn package having a handle portion thereon, a tubular pedestal centrally disposed within said cup and upstanding therefrom, said pedestal fitting within the bore of said yarn package, means for rotating said flyer and means preventing the rotation of the said cup and pedestal; the improvement which comprises flexible pretensioning means for biasing the yarn against the handle portion of said yarn package as it passes from said yarn package to the pedestal, primary tensioning means disposed within said pedestal for regulating tension in the yarn as it passes through said pedestal, and secondary tensioning means associated with said flyer for regulating tension in the yarn while in engagement with the flyer, whereby said twister is adapted for use with a wide variety of types and weights of yarn.
- 15 3. In a twister for imparting two turns to a strand of yarn per each revolution of a flyer, including normally non-rotatable yarn package support means, a flyer rotatable relative to said support means and means for rotating said flyer; the combination with pretensioning means and

4. A yarn tensioning device for two-for-one twisters, housed within the pedestal of said twister, said device comprising a series of parallel pins spaced along a vertical plane in said pedestal, a movable arm, a series of similarly spaced parallel bars carried by said arm, said arm being pivotable about a horizontal axis intersecting the axis of the pedestal to move said series of bars from a position spaced from that of said series of pins to a position where said bars substantially occupy the space between said pins, and a toggle spring biasing said arm from said first position to said second position, the force of said spring increasing as said arm approaches said second position.
5. The device as in claim 4 wherein said movable arm is provided with a bifurcated portion adjacent the pivot axis, said portion terminating in a knife edge, and an annular member is mounted in said pedestal, said member being provided with a diametric V-shaped groove in which said knife edge rocks.
6. The device as in claim 4 wherein a collar is carried threadwise by said pedestal; a re-entrant groove being provided internally of said collar, one end of said toggle

spring engaging said groove, the other end being removably attached to approximately the midpoint of said arm; whereby the projected line of said spring approaches the pivotal axis of said arm as said arm moves to said first position, thereby to reduce the effective leverage on said arm, and recedes from said axis as said arm moves to said second position, thereby increasing the effective leverage on said arm.

7. The device as in claim 6 wherein the first-mentioned end engages said groove with substantially point contact and said other end bears against a knife edge provided intermediate the ends of said arm, whereby the friction between the moving parts of said device is reduced to a minimum.

8. In a two-for-one twister including normally stationary bobbin support means consisting of a cup for the reception of a bobbin having top and bottom flanges, and an upstanding pedestal centrally disposed within said cup and fitting within the bore of said bobbin; improved pretensioning means comprising a multiplicity of flexible members arrayed intermediate the top flange of said bobbin and the top of said pedestal to bias, to a variable extent depending upon the tension in the yarn, the yarn from its normal path of travel between said bobbin and said pedestal to prevent snarling and kinking thereof.

9. In a two-for-one twister including a normally stationary bobbin support platform, an upstanding pedestal carried by said support platform, said pedestal being adapted to extend through the bore of a bobbin and to receive at its upper extremity a yarn end from said bobbin, and a cover carried by said support platform; improved pretensioning means comprising an annular inwardly extending member positioned within said cover and carried thereby, said annular inwardly extending member being adapted to bias a yarn end from its normal path of travel between a bobbin on said support platform and the upper extremity of said pedestal.

10. An improved pretensioning means as in claim 9 wherein said inwardly extending member comprises a circular array of flexible bristles secured to the said cover, said bristles extending inwardly of said cover at an angle less than the normal thereto on a horizontal plane through said cover.

11. In a two-for-one twisting apparatus in which an end of yarn travels under tension in balloon fashion from an orifice in a rotating spindle to an apex guide positioned substantially on the extended axis of rotation of said spindle, improved means for controlling the tension in the yarn balloon comprising in combination a wrap-around thread storage device carried by said spindle to receive the yarn from said orifice and to guide the same into said yarn balloon, said yarn storage device having a yarn engaging surface to frictionally engage said yarn and additionally tension the same a variable amount depending upon the degree to which said yarn wraps around said storage device, various segments of said surface being positioned at different radial distances from the axis of rotation of said spindle such that said yarn, at the point it enters the yarn balloon, is at increasing radial distances from the axis of rotation and the yarn balloon is driven with an effective lever arm of increasing length as the degree of yarn wrap-around on said

thread storage device increases, and a readily and precisely adjustable tensioning means to engage said yarn prior to its contact with said thread storage device so that the tension in the yarn passing to said thread storage device can be adjusted to give a mean degree of wrap-around on said thread storage device to provide an effective lever arm of substantially the optimum length for driving a yarn balloon of any desired one of various types and deniers of yarns.

10. 12. The combination of claim 11 wherein said tensioning means comprises a yarn tension regulator to reduce the magnitude of tension fluctuations in the yarn passing to said thread storage device.

13. The combination of claim 12 wherein said tension regulator is a gate-type regulator positioned within a stationary, cylindrical yarn package support member carried by said spindle.

14. Improved means for controlling the balloon tension in a two-for-one twister comprising a rotatable wrap-around thread storage device for driving a yarn balloon, said storage device having a yarn engaging surface which is at increasing radial distances from the axis of rotation of said storage device with increasing degrees of yarn wrap-around on said storage device so that said yarn balloon is driven with an effective lever arm of increasing length as the degree of wrap-around on said storage device increases, a continuously variable yarn tensioning means to adjustably tension an end of yarn passing to said thread storage device, and readily accessible manipulative means for varying the tension imparted to said yarn by said tensioning means, whereby the tension in the yarn passing to said thread storage device can be adjusted to give a mean degree of wrap-around on said thread storage device which provides an effective lever arm of near optimum length for driving a yarn balloon of any desired one of various types and deniers of yarns.
